US0D1090878S

(12) **United States Design Patent** (10) **Patent No.:** **US D1,090,878 S**
(45) **Date of Patent:** **** Aug. 26, 2025**

(54) **HAND WARMER**

(71) Applicant: **Xiaowei Guo**, Putian (CN)

(72) Inventor: **Xiaowei Guo**, Putian (CN)

(**) Term: **15 Years**

(21) Appl. No.: **29/972,828**

(22) Filed: **Nov. 13, 2024**

(51) **LOC (15) Cl.** **24-01**

(52) **U.S. Cl.**

USPC **D24/206**; D13/108

(57) **CLAIM**

The ornamental design for a hand warmer, as shown and described.

DESCRIPTION

FIG. 1 is a perspective view of a hand warmer, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

All the broken lines in the drawings depict portions of the hand warmer that form no part of the claimed design.

1 Claim, 6 Drawing Sheets
